COMBINED SOAP RECEPTACLE, DRAIN
THEREFOR, AND AIR VENT

William C. Groeniger, Columbus, Ohio, assignor
to John B. Pierce Foundation, New York, N. Y.,
a corporation of New York

Application November 22, 1935, Serial No. 51,014

5 Claims. (Cl. 4—187)

My present invention relates to plumbing devices and more particularly to an improved combined soap receptacle and drain therefor.

In my U. S. Patent No. 2,036,692, issued April 5th, 1936, and entitled Double sink, I have described and claimed an improved double sink, and in my copending application Serial No. 29,904, filed July 5th, 1935, entitled Shear gate valve for dual receptacles, I have described and 10 claimed an improved form of shear gate valve. This shear gate valve is adapted for use in the double sink. As a necessary adjunct to the shear gate there is provided a bearing member for the operating handle thereof.

15 In my copending application Serial No. 759,610, above referred to, I have utilized as the bearing member, a cover plate for the upper open end of the space between adjacent sink bowls, such open space communicating with a common outlet for the double sink. Also, I have incorporated 20 in the cover plate a drainage member, such drainage member being slightly depressed from the upper face of the cover plate.

In my present invention I utilize the cover 25 plate as a soap holder, and attain the advantages of use readily from either sink. I provide also perforations in such soap holder to communicate with the space between adjacent sinks for maintaining the soap holder in sanitary condition.

30 An object of my invention is an improved combined soap holder, drain therefor, and air vent.

An object of my invention is an improved ventilated cover plate for a drain having a soap holder in combination therewith.

35 In the accompanying drawing illustrating a preferred embodiment of my invention,

Fig. 1 is a plan view of a double sink showing my invention mounted in a partition dividing two sinks;

40 Fig. 2 is an enlarged sectional view taken on the line 2—2 of Fig. 1;

Fig. 3 is a fragmentary sectional view taken on the line 3—3 of Fig. 2, and

45 Fig. 4 is a fragmentary sectional view taken on the line 4—4 of Fig. 2.

Referring to the drawing, 10 designates a double sink having the sink compartments 11 and 12 arranged side by side, the sink 10 at its rear face being provided with the usual splash apron 13. In the arrangement shown, adjacent to the compartments 12, is a drain or drip portion 14. In the exemplification shown in Fig. 1, the compartments of the double sink being arranged side by side, the compartment 11 is a laundry sink, 55 while the compartment 12 is the usual kitchen

sink having associated therewith, the drip board 14. The compartments 11 and 12 are separated from each other by the partition 15.

The partition 15 is hollow, and is formed to provide an outlet chamber 16 as shown in Figs. 2, 5 3 and 4. The chamber 16 communicates at its lower end with an outlet sump 17, provided at its lower end with an orifice 30 to which connections with the usual outlet riser are made. Transversely of the length of the chamber 16 10 and intermediate its ends is a partition wall 18 dividing the chamber 16 into two parts. The compartment 11 communicates with one of the parts of the chamber 16 and the compartment 12 communicates with the other part of the 15 chamber 16.

The outlet between the compartment 12 and the adjacent portion of the chamber 16 is indicated in dotted line in Fig. 2 by the reference numeral 19. Associated with the outlet 19 is a 20 shear gate valve 20 similar to the shear gate valve shown and described in my copending application Serial No. 29,904, above referred to. Forming part of the shear gate valve arrangement is a connecting rod 21 and the operating 25 plunger 22.

The upper end of the chamber 16 is open and the sides of the dividing wall 15 which define such chamber laterally terminate at a distance below the closed upper surface of the adjacent 30 portions of the dividing wall 15, as indicated by the reference numeral 23 in Fig. 2.

Closing and covering the depressed open upper 35 end of the chamber 16 is a combined soap receptacle, a drain, and an air vent, this combined structure forming the subject matter of my present invention. This combined structure forms an overflow drain, and a bearing member for the operating plunger of the shear gate valve 20, 40 the details of which are described in my copending application Serial No. 29,904, above referred to. The unit comprising the combined soap dish, drain, and air vent 24, may be secured to the upper end of the wall 15 by screws 25.

The combined bearing member 26 and overflow 45 drain 27 above referred to, are shown as depressions in the cover plate 24 at or adjacent the opposite ends thereof. That intermediate portion of the cover plate 24 between the overflow drain and bearing member, may lie in substantially the same plane as the upper closed end of the wall 15. The upper surface thereof is depressed as indicated by the numeral 28, to form a receptacle for a cake of soap or other cleansing 50 agent. The bottom of the depression is pro- 55

vided with a plurality of drain holes or slots 29 through which water or other liquid may flow into the outlet chamber 16.

My improved soap receptacle is thus practically an integral part of the sink structure, is preferably made from the same material, usually vitreous material, and is always self-draining into waste outlet. In addition, such receptacle, while maintaining the soap or other cleansing material, always ready for use, may be as readily cleaned as the sink itself.

While I have necessarily shown and described the preferred embodiment of my invention, somewhat in detail, it is to be understood that I may vary the size, shape and arrangement of parts, as well as the material thereof, comprising my device, within relatively wide limits without departing from the spirit of the invention.

I claim:

1. An improved combined soap receptacle and drain therefor comprising, a hollow wall structure for a double sink, said wall structure being open at the top and constituting a drain for the sink, a cover for said open top of the wall structure provided with perforations adjacent to each end to permit flow of liquid from the sinks into the drain, and a soap receptacle arranged between the said end perforations.

2. An improved combined soap receptacle and drain therefor comprising, a hollow wall structure for a double sink, said wall structure being open at the top and defining a drain for both of the sink elements, a cover for said open top provided with groups of perforations adjacent to each end to permit flow of liquid from the sinks into the drain, said groups of perforations acting as an overflow for the sinks, and a soap receptacle formed integral with the cover, and ar-

ranged between said groups of perforations, and having its bottom perforated and lying in a plane above the plane of the groups of perforations.

3. A combination overflow drain and soap receptacle for a sink structure having a hollow wall a portion of which is depressed and open at the top, which comprises a plate adapted to cover the open top of the depressed portion of the hollow wall, said plate being provided with perforations for function as an overflow drain for the sink structure, and said plate having further a perforated raised formation intermediate its ends for function as a self-draining soap receptacle.

4. In combination with a sink having a lateral main drain controlled by a shear gate valve, a cover plate disposed above said main drain and provided with perforations communicating with said main drain and functioning as an overflow drain, bearing means formed in the cover plate for the operating handle of the shear gate valve, and a soap receptacle formed in the cover plate at a level above that of the said perforations, said soap receptacle draining into the said main drain.

5. In combination with a double sink having a hollow wall forming the outlet passage for wastes from the component sinks, and having lateral outlets opening into the outlet passage and controlled by shear gate valves, a structure forming the top of the hollow wall, said structure including perforations functioning as an overflow drain, mutually spaced bearing structures for the reception of the operating handles of the said shear gate valves, and a soap receptacle disposed between said bearing structures at a level above that of the said perforations and draining into said outlet passage.

WILLIAM C. GROENIGER.
